UNITED STATES PATENT OFFICE

CLARENCE E. SAFFORD, OF CLEVELAND, OHIO, ASSIGNOR TO ALTON H. GREELEY, OF CLEVELAND, OHIO

HEAT-EXCHANGE APPARATUS

Application filed May 12, 1925. Serial No. 29,680.

This invention relates to the construction of devices adapted to heat, cool and condense fluids by means of other fluids through indirect action, and the objects of this invention are to produce a heat exchange apparatus which, first, will have a maximum capacity for the space occupied; second, wherein the contained fluid may freely circulate and thus conduce to rapid interchange of heat; third, wherein there are no pockets to retard the flow or to hold fluids when the device has been installed thus avoiding all danger of corrosion; fourth, which shall be constructed of thin sheet metal which will permit rapid interchange of heat; and fifth, which will be so light that it can be handled and installed with minimum labor.

This invention is embodied in a heat exchange apparatus formed of two sheets of metal bent into a succession of folds whose ends are brought together and permanently secured together by brazing or welding, the lateral edges of the sheet being permanently united, and the edges of the sheet metal between the joints at the ends of the folds being flattened and permanently secured to trough-shaped strips of metal which are preferably segments of cylinders so as to completely close the apparatus at the edges of the folded sheets.

It further consists in interlocking members for supporting and sustaining the walls of this apparatus against pressure.

It also consists in so attaching to the corners of the apparatus one or more pipe coupling members of larger curvature than the trough-shaped strips to which the folded sheets are attached so that when the apparatus is installed it may drain through said coupling members.

It also consists in the details of construction shown in the accompanying drawings and particularly pointed out in the claims.

This application furthermore, in part, constitutes a continuation of my pending application Serial No. 329,218 filed Oct. 8th, 1919, allowed November 20th, 1924.

In the accompanying drawings:

Figure 1 represents a side elevation of a device embodying my invention;

Fig. 2 represents an end elevation of this improved heat exchange apparatus;

Fig. 3 represents a plan with a portion of the upper end broken away;

Fig. 4 represents a transverse vertical section of the upper end of the apparatus; 55

Fig. 5 represents a section on the line 5—5 of Fig. 4;

Fig. 6 is a perspective view of the top of this apparatus; 60

Fig. 7 represents a perspective view of a section of one of the folded sheets employed to construct the apparatus.

Similar reference characters refer to like parts throughout the several views. 65

The illustrated embodiment of my invention includes two sheets of metal, a pair of trough-shaped strips to which the ends of the sheets may be secured connecting members to take up the stresses caused by the pressure 70 within or without the apparatus, and means to connect pipes to the apparatus.

The two sheets 1 and 2 are first cut to proper form and then folded, the flanges 3 at the ends of the folds 4 being brought together and 75 secured together by brazing or welding. The edges of the sheets between the flanges 3 constitute flanges 5 which are attached to the trough-shaped strips 6. These strips between the flanges 5 are preferably segments of cylinders 80 but may be of any other desired cross-section.

The lateral edges of the sheets are formed into straight flanges 7 which are attached to each other and to curved flanges 8 which fit 85 around the coupling members 9 at the corners of this apparatus. These coupling members are usually internally threaded for part of their length but their inner ends are preferably left blank and fit the outsides of the 90 adjacent ends of the trough-shaped strips 6. These strips may be made of considerably thicker metal than the parts 1 and 2. The sheets may be formed with flat portions 10 adjacent to the lateral edge flanges 7 which 95 constitute troughs connecting with the coupling members at the ends thereof.

I prefer to secure pairs of angle bars 12 to the opposite faces of the curved portions 13 of the sheets 1 and 2, as shown in Figs. 4 and 100

5, by welding or otherwise, and form feet 16 on the ends of these bars, which feet are attached to the flat portions 10 of the parts 1 and 2. One of these bars of each pair is secured to the part 1 and the other bar of each 5 pair is secured to the part 2. Each bar is formed with larger and smaller indentations, or, in other words, with oppositely extending 10 projections 14 and 15, the projections 14 of one bar of each pair fitting into the indentations produced by forming the projections 15 on the other bar of the pair. The sides of these projections 14 are flat so as to produce a strong interlock. The inner curves 13 of 15 the folds of each side are spaced apart from the similar curves of the opposite side so as to leave a large space through which the fluids may flow freely.

After the sheets are folded and formed as 20 shown in Fig. 7, the bars 12 are attached thereto and the two halves are brought together and the flanges 7 united. The couplings 9 are attached to the strips 6 and these parts are then positioned between the flanges 5 and 8. While held in position these flanges 25 are attached to these strips and coupling members by brazing or welding. This completes the apparatus. It will be apparent that instead of two sheets 1 and 2 a single 30 sheet may be properly cut and folded so as to constitute both sides of this apparatus, and being of thin metal and therefore flexible, the interengagement of the projections on the reinforcing bar offers no difficulty. It will 35 also be apparent that the forms and dimensions of the folds may be changed within very wide limits and that the proportions of the various parts may all be changed without departing from the spirit of my invention as 40 set forth in the following claims.

This apparatus is adapted for heating and 45 cooling buildings and heating, cooling and condensing liquids, vapors and gases under all conditions. When the folds are vertical and vapors are confined therein, the liquids which result from condensed vapors will be received by the smooth trough-shaped strip 6 at the bottom of the apparatus and flow to one of the coupling members. As the thickness 50 of the wall of the pipe 17 (Fig. 3) which screws into the coupling member is no greater than the thickness of the strip 6, there will be no damming of the liquid which will flow away freely.

55 As the structure of this apparatus is the same at both strips 6 there is no possibility of any liquids, either heavy or light, being pocketed, and therefore no possibility of any liquid being lodged sufficiently long to cause corrosion. When the structure is placed with the strips 6 vertical, liquids will flow in either direction along the troughs formed by the parts 10 of the sides to the lowest coupling, the couplings being preferably cut away at 60 18 to permit free flow of the liquid. So long as

the plane passing through all of the couplings is vertical, there are no pockets in which the fluids may lodge, no matter at what angle the strips 6 may be to the horizontal. All the edges of this structure between the coupling 70 members are straight and free flow of liquids is thereby insured.

The folds 4 branch laterally from the central passages formed in part by the strips 6 so that fluids entering any coupling member 75 will be unobstructed in their passage to every part of the entire structure, and from every part to the discharge passage.

In the construction of the folds or corrugations, the sheet metal is merely bent and is 80 not stretched to any degree so that the danger of cracks being formed is practically absent. If the sheets were so bent and stretched as to bring the flanges 5 together, the metal would be made very thin in spots and pockets would 85 be formed where liquids could collect and where rusting would be inevitable. Furthermore, the pockets are absent at both the top and the bottom of the structure so that when 90 employed in steam heating, neither air nor water can collect and hammering is eliminated.

Fig. 4 shows the inner faces of the substantially semi-cylindrical portions 13 of the 95 sheets 1 and 2, quite close together, and the flanges 5 which engage the edges of the trough 6, much further apart. The upper and lower ends of these parts 13 or faces of the corrugations are curved outwardly and flattened until they merge into the flanges 5. When the spaces between the faces 100 13 and the flanges 5 are substantially equal, the metal must necessarily be greatly stretched to fit against the troughs 6. But by so proportioning the parts that the end portions can be curved gently outward to a straight line, substantially no stretching occurs.

The manner of forming the halves of the 105 radiator provides, when the flanges 7 are united, a seat at the top and at the bottom of the radiator structure for the reception of the trough-shaped strips or members 6, the seat being provided by the flanges 5. By 110 means of this construction the trough-shaped strips or members 6 may be placed within the seat and welded in place through the continuous sides of the seats formed by the flanges 5.

115 What I claim is:

1. In a heat exchange apparatus, the combination of a pair of sides folded, bent and welded to produce parallel corrugations having closed ends, the ends of the inner portions of the corrugations being flattened and curved outwardly until they constitute continuous parallel flanges located beyond said corrugations, trough-shaped strips bridging the spaces between the flanges and attached thereto and means connecting across between 120 125 130

said inner portions of the corrugations between the ends thereof, to stiffen the structure.

2. In a heat exchange apparatus, the combination of a pair of sides folded, bent and welded to produce parallel corrugations being substantially semi-cylindrical between their ends, the ends of said inner portions of the corrugations being curved outwardly until they constitute parallel flanges at the closed ends of said corrugations, the length of the end edges of the sides remaining the same, and trough-shaped strips united to and bridging the spaces between the flanges, the side edges of the sheets being united and bent to form troughs which extend between the ends of said trough-shaped strips, and coupling members united to said sides at the meeting points of said troughs.

20 3. In a heat exchange apparatus, the combination of a pair of sheet metal sides formed to produce corrugations having closed ends, trough shaped members bridging separated portions of said corrugations, coupling members connected to the ends of the trough shaped members and to the sheet metal sides adjacent thereto, and means connecting across between the sheet metal sides intermediate the ends thereof and connected to the adjacent bottoms of the corrugations and comprising bars having inter-engaging portions.

4. In a heat exchange apparatus, the combination of a pair of sides folded, bent and welded to produce corrugations having closed ends, trough-shaped strip members bridging the separated portions of said corrugations, and cylindrical coupling members connected with said strip members and the metal constituting said sides at the ends of said strip members, and angle bars, one on each side, having interlocking parts adapted to hold said sides against separation.

5. In a heat exchange apparatus, the combination of a pair of sheet metal sides bent into a succession of outwardly projecting folds and with the ends of the folds brought and permanently fastened together and with the edges of the metal between the folds constituting continuous flanges extending beyond such folds, the flanges at adjacent ends of the two sheets being spaced apart to form seats, and trough-shaped strips in said seats and welded to said flanges, the lateral edges of the sheets being attached to each other, and coupling members attached to said strips and projecting beyond the sides of the structure, the metal of the sides being formed to constitute flanges which fit about and are welded to said coupling members.

6. In a heat exchange apparatus, the combination of a pair of sheet metal sides bent and formed to produce a plurality of alternating inwardly and outwardly projecting corrugations, the ends of the outwardly pro-

jecting corrugations being brought together and closed and the ends of the inwardly projecting corrugations being flattened and curved outwardly and terminating in flanges which extend beyond the ends of the first mentioned corrugations, the said flanges being in such proximity as to constitute a continuous flange at each end of each side and such continuous flanges at adjacent ends of the said sides forming a seat, and a trough-shaped member in each seat and having its sides welded to the flanges thereof, the lateral edges of said sides being provided with longitudinal flanges by which they are welded together, the ends of the last mentioned flanges being spread apart and shaped to form seats, coupling members on the ends of the trough-shaped members and resting in the last mentioned seats and welded thereto.

7. In a heat exchange apparatus, the combination of a pair of sheet metal sides folded, bent and welded to produce corrugations having closed ends and having at each end thereof and beyond such corrugations a continuous flange, trough-shaped strip members interposed each between the flanges at adjacent ends of the sides and welded thereto, the lateral edges of said sides being welded together and so shaped as to provide outwardly projecting troughs at such united edges, and coupling members connected to the ends of the trough-shaped members and to the sheet metal sides adjacent thereto, the aforesaid troughs communicating at their ends with a fluid-receiving space constituted by the trough-shaped members and coupling members.

8. In a heat exchange apparatus, the combination of a pair of sheet metal sides bent into a succession of outwardly extending folds and with the ends of the folds permanently fastened together, the metal between the folds providing continuous flanges spaced apart to form a seat for a trough shaped strip, a trough shaped strip engaging said flanges and having its outer edges permanently secured thereto, the lateral edges of said pair of sides being permanently secured to each other and shaped to provide inlet and outlet openings and coupling members disposed within said openings and secured to said trough shaped strip.

Signed by me this 6th day of May, 1925.
